UNITED STATES PATENT OFFICE.

BERNARD I. MAHON, OF SANBORN, IOWA, ASSIGNOR TO BRADY BROS. AND KERBERG, OF SANBORN, IOWA, A FIRM.

HEATER.

SPECIFICATION forming part of Letters Patent No. 760,226, dated May 17, 1904.

Application filed January 19, 1904. Serial No. 189,741. (No model.)

To all whom it may concern:

Be it known that I, BERNARD I. MAHON, a citizen of the United States, residing in Sanborn, in the county of O'Brien and State of Iowa, have made certain new and useful Improvements in Heaters, of which the following is a specification.

The object of my invention is to provide an improved water and air heating attachment for stovepipes, the same being in practice applied to the pipe at any desired point and generally in a room or apartment separate from that in which the stove or furnace is located. The attachment utilizes the heat derived from the products of combustion passing through the pipe and is adapted to contain water, which may be drawn off for any desired purpose and at the same time radiates heat into the room or apartment.

The details of construction, arrangement, and combination of parts are as hereinafter described, reference being had to the accompanying drawings, in which—

Figure 1 is a central vertical section of the heater in perspective. Fig. 2 is a horizontal section on the line 2 2 of Fig. 1. Fig. 3 is a perspective view showing the several parts of the heater disassociated. Fig. 4 is a vertical section of the lower or base portion of the heater. Fig. 5 is a similar section of the top rim of the heater. Fig. 6 is an enlarged cross-section of one of the panels or side plates of the heater.

As shown in Fig. 1, the heater proper is supported by legs or brackets *a*, which may be secured to the base portion *A* in any approved manner. The body or main portion *B* of the heater is a cylinder, having a flat top and a conical bottom and a series of lateral projections *b*. Upon such body portion is applied the top rim *C*, and a cover *D* completes the heater. The base portion *A* and the cap or cover *D* are provided with central tubular extensions *a'* and *d*, respectively, which are adapted to be connected with and form practically part of the stovepipe. The cover *D* has a pendent flange, which when the cover is in place fits within the annular rim

C, as shown in Fig. 1. As shown in Fig. 5, the lower edge of the rim *C* is constructed with an annular socket *c*, the same being formed by bending up the lower edge of the sheet metal and forming a reversed curve, so that in cross-section it approximates an **S** shape. The socket *c* serves to receive the top flanges *b'* of the body portion or water-holder *B*, for, as shown in Figs. 1 and 2, each one of the lateral projections *b* of the water-holder has flanges at top and bottom and also on the sides, the side flanges being marked *b'*. As will be understood by reference to Figs. 2 and 3, the separation of the projecting portions *b* provides spaces through which the products of combustion pass upward and converge to the tubular portion *d* of the cap *B*. For closing these spaces on the outer side I provide a series of elongated rectangular panels *b''*. The same are shown in face view and reversed in Fig. 3 and in cross-section in Fig. 6. Each panel is provided with reversed curves on the sides, which form sockets *b'''*, adapted to receive the flanges *b'* of the water-heater *B*. The panels are made of such length that their upper ends project and constitute virtually so many flanges adapted to enter the sockets *c* of the rim *C* in the same manner as the top flanges *b'* of the water-heater *B* enter the sockets *c*. It is apparent that the panels *b''* are inserted in place by sliding them endwise from the top down or from the bottom upward, and that when in place they form a practically smooth continuation of the outer side of the water-heater *B*. As shown in Fig. 4, the base portion *A* is formed with a top socket *a''* in the same manner as the lower edge of the rim *C*. The same is also plainly indicated in Figs. 1 and 2. This socket *a''* receives the lower flanges *b'* of the water-heater and the lower ends of the panels *b''*, as will be readily understood. Thus in setting up my improved heater the water-holder *B* is first set in place upon the base *A*, its flanges *b'* entering the socket *a*, as plainly indicated in the drawings. If the panels *b''* have been previously set in place on the water-heater, then the lower edges of the panels will enter the socket *a''* at the same time

as the flanges b' of the water-holder; but it will be understood that the panels b' may be inserted in place after the water-holder B has been set on the base A. Either mode of manipulation is practicable. The next step is to place the rim C on the water-holder B, so that its socket c receives the top flanges b' of the water-holder and the ends of the panels b' . In order to secure all these parts A, B, and C firmly together, I employ tie-rods E, (see Figs. 1 and 2,) the same being engaged at their upper ends with perforated brackets c' and passing down through the bottom of the base A, where they will be provided with nuts for tightening them to the required degree. It is apparent that by removing the nuts all the parts A, B, and C may be readily detached from each other, if required, for the purpose of cleaning or repairing the heater. The cover 20 D is held in place solely by friction with the rim C, in which its pendent flange is inserted. The cover is thus adapted to be readily detached for the purpose of cleaning the interior of the heater or, in other words, brushing off any soot that may have accumulated thereon. The cover is provided at d' with a removable cap, which covers a tubular passage that communicates with the water-passage b^9 of the water-holder B in such manner 30 that water poured therein will fill the holder. In other words, the body or cylindrical portion of the heater B has a series of lateral holes b^5 , by which communication is established with the lateral chambers formed by the projecting parts b . The body of the water-holder B is, however, cut away at the top, as shown at b^6 , so that water entering the passage b^9 may enter the large central chamber as well as the small lateral one b . A spigot b' is provided for drawing off water from the holder B, the same being applied at the lower end of one of the lateral chambers b . The bottom portion of the water-holder b^8 is constructed as a cone, the apex of the same being near the 45 center of the opening in the base A. This construction not only provides a larger heating-surface than would be obtained if the bottom of the water-holder were horizontal or flat, but also serves to divert the entering current of products of combustion to the several vertical passages or flues formed between the lateral chambers b .

In practice the panels b' may be made of burnished tin or brass or of any other material presenting a different appearance from the body of the heater, whereby the ornamental effect will be enhanced.

As thus constructed my improved attachment for stoves or other heating-pipes is ornamental in appearance and highly efficient in use, since it serves both as an air-heater and a water-heater which is independent of water-pressure and to which water may be readily supplied when required.

Having thus described my invention, what I claim as new, and desire to secure by Letters Patent, is—

1. The improved heater comprising a base portion having a top socket, a top rim having a bottom socket, and the intermediate body portion formed as a water-heater, the same comprising an inner cylinder having a series of lateral projections serving as water-chambers and provided with flanges which are adapted to enter the sockets of the base and top portions, substantially as described. 75

2. In a heater of the class specified, the combination with a base portion having a socket, a top portion having a similar socket, and a body portion having lateral projections provided with flanges adapted to enter the sockets of the top and bottom portions, and panels which close the spaces between the lateral chambers and also enter the said sockets, substantially as described. 80

3. In a heater of the class specified, the combination, with base and top portions having sockets, of the body or intermediate portion having laterally-projecting portions serving as chambers and provided with flanges adapted to enter the sockets, substantially as described. 90

4. In a heater of the class specified, the combination, with the base and top portions provided with sockets, of the body or intermediate portion having a series of lateral projections forming chambers that communicate with the main chamber of the body, the said lateral chambers having end projections or flanges adapted to enter the aforesaid sockets, substantially as described. 95

5. In a heater of the class specified, the combination, with a base portion and a body portion seated thereon and having a series of lateral projections that constitute lateral chambers, the same being provided with side flanges, of panels having lateral sockets adapted to receive said flanges, substantially as described. 105

6. In a heater of the class specified, the combination, with the body portion having a series of lateral projections forming chambers and provided with lateral flanges, of panels having lateral sockets adapted to receive said flanges, the panels being thus slidable on the flanges so that they may be inserted and removed as occasion requires. 110

7. In a heater of the class specified, the combination, with a suitable base-support and a body portion having lateral projections forming chambers, of a series of panels which are detachably connected with the lateral chambers and serve to close the spaces between them, and thus form flues or smoke-passages in the manner described. 120

8. In a heater of the class specified, the combination, with the base-support having a socket at its upper edge, of the body portion having an interior chamber and a series of lateral 125

projections arranged vertically and forming lateral chambers that communicate with the interior chamber, said lateral chambers having flanges on the sides and bottom, and re-
5 movable panels having sockets adapted to receive the lateral flanges of the side chambers, and their lower ends entering the socket of the base portion together with the flanges of the side chambers, substantially as described.
10 9. In a heater of the class specified, the com-

bination, with the base portion having a central opening in its bottom portion, of the body portion or water-holder having a series of lateral projections that serve as water-chambers, the central and larger chamber having a con- 15 icial bottom, substantially as described.

BERNARD I. MAHON.
